UNITED STATES PATENT OFFICE.

LUDWIG MARSCHALL, OF NEW YORK, N. Y.

FLYING-MACHINE.

1,117,585.

Specification of Letters Patent. Patented Nov. 17, 1914.

Application filed March 28, 1914. Serial No. 827,859.

To all whom it may concern:

Be it known that I, LUDWIG MARSCHALL, a subject of the German Emperor, residing at New York, in the county of New York 5 and State of New York, have invented certain new and useful Improvements in Flying-Machines, of which the following is a specification.

My invention relates to machines for navigating the air and has for its object to imitate the flying of large birds, as eagles, etc.

The invention consists in certain novel features in construction and combination of parts, as will be hereinafter fully described 15 and set forth in the annexed claims.

It comprises a skeleton frame work equipped with two conchylaceous wings, or wings that are so shaped as to resemble the wings of large birds and whereby the principle involved in the maneuvers by flying birds will be complied with. The wings are arranged or hinged on horizontal axes and by suitable means are adapted to be moved up and down so that, owing to their shape, 20 the air pressure will affect the machine in two directions, to wit, in a vertical direction which is due to the vertical reaction owing to which the machine will be lifted, and in a forward direction owing to the air pressure 25 against the circularly curved, forward surfaces of the wings.

Another object of my invention is to provide the wings with suitable counterbalancing means, so that the force required to move 30 the wings during the flight or at the start will be greatly reduced.

My invention will be fully understood by reference to the accompanying drawings, in which similar reference characters denote 35 corresponding parts and in which—

Figure 1 is a rear elevation of the flying machine; Fig. 2 is a top plan view thereof; Fig. 3 is an enlarged section on line 3—3 of Fig. 2; Fig. 4 is a perspective view of the 45 motion transmitting means and Fig. 5 is a longitudinal section of a wing on line 5—5 of Fig. 2.

Referring specifically to the drawing 1 denotes a skeleton frame work of any suitable 50 construction in which are journaled two horizontal spindles 2. These spindles carry each a pair of rocking levers 3, 3' which in the present example of my invention are

angular levers reinforced by braces 3². At one end each pair of angular levers carry 55 a horizontal spindle 4 and at the other end a counterbalancing weight 5.

Suitably fastened to the spindle 4 are wings 6 one on each side of the machine, which by rocking the lever 3, 3' are swung 60 in vertical direction up and down. Each wing consists of a light but strong frame work composed of slats 9', 9² and 9³ and canvas 10 or other suitable material stiffened at its edges and curved by suitable 65 means to give the wing a conchylaceous shape, as shown in the drawings, particularly in Figs. 2, 3 and 5. The front edge 10' of each wing is shaped substantially as shown in Fig. 2, i. e. at its outer free end 10³ 70 the wing is almost pointed, that is to say, the front edge 10' almost coincides with the rear edge 10² and then gradually curves outwardly to a point at which the wing is largest in width. From this point it is curved 75 first inwardly and then again outwardly.

The rear edge 10² of each wing is straight. In cross section as seen from Fig. 3 the surface of the wing rises gradually from its rear edge 10⁴ and then makes a circular 80 curve downwardly to the front edge 10' which lies in the same plane as the rear edge 10². At the inner end, as at 10⁴, each wing is curved in the arc of a circle downwardly and its edge 10⁵ is curved inwardly and upwardly as seen from Fig. 5. By reason of this shape when the wing is swung downwardly the air will flow in the direction indicated by dotted lines in Fig. 2, and while the vertical resultant of the air pressure will lift 85 the machine, the pressure against the curved forward surface will propel it forwardly. A part of the air will flow toward and into the hollow 10⁶ formed by the curved edge 10⁵, whereby the air pressure will be deflected upwardly against the wing and tend 90 to swing the wings back into lifted position. The weights 5 and spring 6 serve as counterbalancing means for the wings. Instead of the weights and the spring, or in addition 95 thereto, other counterbalancing means may be provided; as for instance, a pneumatic counterbalancing mechanism, such as shown at 7 in Fig. 1.

The operation of the levers 3, 3' may be 100 accomplished in any suitable manner. In

the present example I have shown levers 8 pivoted at 8' to arms 8² and connected to 5 rocking bars 11. The arms 8² are fixed to arms 8³ which are rotatively mounted on the spindles 2 (Fig. 4) and engage at their upper ends the spindles 4 (Fig. 3) which carry 10 the wings 6. The rocking bars may be driven by hand, or, as shown in the present example, from a motor 12 which through suitable transmission gears imparts motion 15 to a gear 13. By means of a crank 14 motion is transmitted in any suitable manner to the rocking bar 8.

Since various modifications may be made 15 in the construction of the machine by those skilled in the art without departing from the principle of my invention, I do not wish to limit myself to the details shown and described.

What I claim and desire to secure by Letters Patent is;

1. A flying machine, consisting of an aeroplane composed of two wings, capable of swinging in vertical direction, rocking levers carrying said wings at one end and 25 counterweights carried by the other end of said levers.

2. In a flying machine, a frame, vertically swinging levers hinged to said frame, a wing secured to one end of each rocking 30 lever and a counterweight carried by the other end of each lever.

In testimony whereof I affix my signature in presence of two witnesses.

LUDWIG MARSCHALL.
